UNITED STATES PATENT OFFICE

1,932,288

WRINGER

Gustave H. Jantz, Wyoming, Ohio

Application August 31, 1931. Serial No. 560,401

15 Claims. (Cl. 68—32)

This invention relates to wringers of the character of those employing opposed wringer rolls between which the goods are arranged to be passed for expressing the liquid therein.

5 It is the object of the invention to provide a new and improved structure of wringer frame; further, to provide a novel wringer frame structure capable of being formed out of sheet metal; further, to provide a wringer frame structure 10 comprising a base and uprights at the respective ends thereof formed out of a single piece of sheet metal; further, to provide a novel base for a metal frame wringer; and, further, to provide a novel arrangement of shelves, upright flanges 15 and separated upright posts in a sheet metal wringer structure.

It is the object of the invention further to provide novel means for securing end clothes guards to the upright posts; further, to provide 20 a novel drain board arrangement; further, to provide novel releasing means between the separable frame sections; and, further, to provide a novel means for limiting separation between the frame sections.

25 The invention will be further readily understood from the following description and claims, and from the drawings, in which latter:

Fig. 1 is a front elevation of a clothes wringer embodying the invention.

30 Fig. 2 is an end view of the same.

Fig. 3 is a vertical longitudinal central section, taken on the line 3—3 of Fig. 2.

Fig. 4 is a sectional detail view of the separation limiting means, taken on the line 4—4 of 35 Fig. 2.

Fig. 5 is a cross-section of the same, taken in the plane of the line 5—5 of Fig. 4.

Fig. 6 is a cross-section of the exemplifying 40 wringer, taken on the line 6—6 of Fig. 1.

Fig. 7 is a cross-section of the same, taken in the plane of the line 7—7 of Fig. 3.

Fig. 8 is a horizontal section of the same, taken in the plane of the line 8—8 of Fig. 3.

Fig. 9 is a horizontal sectional detail view, 45 taken in the plane of the line 9—9 of Fig. 7.

Fig. 10 is a front elevation of one end of the wringer, showing a modification of the frame structure, partly broken away.

Fig. 11 is a cross-section of the same, taken on the line 11—11 of Fig. 10, partly broken away; and,

Fig. 12 is a horizontal section of a detail of the same, taken on the line 12—12 of Fig. 10.

The frame of the wringer comprises a base 21 55 and upright posts 22, 23, at the respective ends

of the base. The base comprises oppositely downwardly sloping shelves 24 at the respective sides of the wringer, from the respective ends of which flanges 25 project upwardly, the lower ends of the flanges and the respective ends of the shelves having curved bends 26 in the angles between said shelves and flanges. The frame structure is preferably formed up out of sheet metal.

The upright posts are shown hollow to form 65 channels 27 in which bearings 28, 29, for the wringer rolls 30, 31, are received. These bearings are preferably of wood impregnated with lubricant. One or more of the upright walls are bent upwardly from the respective ends of the 70 base in the sheet metal structure. Three of such walls are shown thus bent upwardly in the preferred form of the invention shown in Figs. 1 to 9 inclusive, including an inner wall 32 and the side walls 33. (Fig. 9). In the modification 75 shown in Figs. 10 to 12 inclusive, the outer wall 34 of each of the posts is shown bent upwardly from the base. These upright walls are located between the side flanges. The side flanges are shown extending throughout the major portion 80 of the height of the upright posts, and preferably flare endwise outwardly toward their lower ends, as at 35. (Fig. 3).

The outer edges of the shelves and flanges are rounded, as shown at 36, and the outer margins 85 of the shelves droop as shown at 37, the ends of the shelves merging with the lower ends of the flanges in sweeping curves, and the outer upright edges of the bends and flanges preferably slope inwardly, the lower portions 38 of the slope 90 (Fig. 7) being more abrupt than the slope 39 of the upper portion thereof, the upper ends of the flanges preferably meeting the upright posts with an upper rounding 40 below the lower edge of the top bar 41.

The shelves and the flanges and walls of the post extending upwardly from the shelves are 95 preferably formed out of a single sheet of sheet metal.

In the form shown in Figs. 1 to 9 inclusive, 100 the walls 32, 33, form oppositely presented substantially U-shaped channel walls which open outwardly. (Fig. 9). The outwardly presented openings have plates 45, 46, extending thereacross, the margins of which are connected with the flanges, as by lapping joints 47, the margins being connected with the upright walls by suitably welding the same thereto.

The lower ends of the plates 45, 46, are curved 105 inwardly, as at 48, (Fig. 3), following the curva- 110

- ture of the bends between the lower portions of the upright flanges and the outer portions of the shelves, and preferably part-way close the lower ends of the channels, leaving openings 49, in said lower ends for permitting draining of liquid from the channels.
- The inner upright wall of each of the channels is provided with an upright slot 51, in which the roll shafts 52, 53, of the wringer rolls are received.
- 10 One of the outer walls of the channels is provided with a slot 54 through which the operating end of the shaft of the lower wringer roll extends. This operating end may be suitably formed for connection with a suitable operating device, either manual or power.
- 15 A support 57 is located in the lower portion of each of the upright channels, being shown as a block fixed to the inner wall of the upright channel by a screw 58. The lower bearings for the wringer rolls rest on these blocks.
- 20 A clothes guard 61 is located at each end of the wringer rolls and has a marginal flange 62 along the front and rear and lower margins of the same, the lower portion of the marginal flange sloping downwardly and inwardly, as shown at 63. The margin of the flange is rounded for instance by a curl 64. Each clothes guard is provided with an upright slot 65. The shafts of the wringer rolls are located in these slots.
- 25 The respective walls of each of the slots 65 are provided with outwardly extending flanges 66 located between the opposing edges of the slot 51 in the inner wall of the upright post, the slot 51 being enlarged at said flanges for forming shoulders 67 upon which the lower ends of the flanges 66 preferably rest for limiting downward movement of the clothes guard, the flanges locating the clothes guard on the upright post in directions in the plane of the clothes guard. The inner wall 32 of the upright post is provided with slots 71 having enlargements 72 through which the heads 73 of pins 74 fixed to the clothes guard are received, the clothes guard being then lowered for locating the shanks of the pins in the narrower portions of said slots for holding the clothes guard toward the post.
- 30 A drain board 77 is located between the base and the lower wringer roll. This drain board may be tilted for sloping toward either one of the downwardly and outwardly sloping shelves for draining the water toward the tub. The front and rear edges of the drain board are provided with drooping margins 78, (Fig. 6), and the respective ends of the drain board are provided with upwardly extending flanges 79, the outer ends of which are provided with curved bends 80 (Fig. 1) connecting with the bottom of the drain board. The end flanges of the drain board are pivoted at their middle portions on the screws 58.
- 35 The bottom face of the drain board is provided with a knob 81. (Fig. 6). A spring 82, shown as a leaf spring, is fixed, as by rivets 83, to the under face of the base, which has an opening 84, into which a curved portion 85 or hump of the spring extends, this hump coacting with the knob for resiliently holding the drain board in assumed tilted positions, but permitting tilting of the drain board by forceful movement thereof.
- 40 The top bar 41 has a top wall 91, depending side walls 92, and depending end walls 93, 94, forming a hollow 95 in the top bar. (Figs. 3, 4, 5, 6 and 8). The top bar connects the upper ends of the upright posts, being received canopywise over said upper ends, and is arranged to be releasably secured to the upright posts for per-
- mitting pressure upon the wringer rolls when the top bar is held in position, and permitting relief of such pressure when the top bar is released.
- The connecting means between the top bar and the frame proper of the wringer are exemplified as comprising a knob 96 and a hole 97, the wall of which coacts with the knob at one end of the top bar, the knob being shown on the outer wall of the upright post 23 and the hole in the end wall 94 of the top bar. There is a latch 80 at the other end of the wringer which is exemplified as comprising a latching bar 101, exemplified as a leaf spring, the lower end of which is fixed to the wringer frame. (Figs. 1, 2, 3, 4 and 8). It is shown provided with a curved bend 85 at 90 conforming to the curvature of the bend 48. It is mounted on the plate 45 in the preferred form of the invention. The points of attachment of the leaf spring are at the lower end thereof, as by welding at 103.
- Latching parts are located between the upper end of the latching bar and the end wall 93 of the top bar, shown as a lug 105, or bolt normally received in an opening 106 in the end wall 45, and arranged to be received in an opening 104 in the end wall 93 of the top bar, and coacting with the lower wall of said opening 104 for latching the top bar to the main frame, the bolt having a rounded upper end 107 against which the lower edge 108 of the end wall 93 contacts for moving the bolt outwardly by downward movement of the end wall and locating the opening 106 in the end wall opposite the bolt for latching the top bar to the wringer frame.
- An endwise movable rod 111 is slidable in bearings 112, 113, fixed to the top bar. (Figs. 3, 4, 5 and 8). The rod is normally resiliently held inward by a spring 114, coiled about a reduced portion of the rod between the bearing 112 and a shoulder 115 on said rod. The outer end of 110 the rod is arranged to pass through the opening 106 in the end plate 45, and through the hole 104 in the end wall 93, and to move the upper end of the latch bar 101 outwardly for releasing its bolt 105 from its complemental keeper or wall 120 in the opening 104, for permitting release of the top bar.
- A sleeve 121 is journaled in a bearing 122 fixed to the top bar. (Figs. 3, 6, 7 and 8). This bearing may be made in halves, having a parting line 123 between them crosswise of the top bar, the respective halves being provided with flanges 124 fixed to the top wall of the top bar, as by welding. The sleeve is journaled in this bearing and has opposed shoulders 125, 126, between 120 which the bearing is located.
- The lower end of the sleeve has wings 127 projecting therefrom forwardly and rearwardly, and forming cams coacting with the end face 128 of the rod 111 for moving said rod upon 125 rocking movement of the sleeve. These wings are shown provided with corners 129 acting to quickly move the reciprocating rod to full extent for release of the top bar with a rocking movement of the sleeve throughout only a short 130 angle. The sleeve is provided with arms 130, normally projecting therefrom parallel with the top bar, and provided with handles 131 at their ends. Pulling or pushing upon either of said handles crosswise of the top bar rocks the sleeve 145 and quickly releases the latching means.
- A spring 135, shown as a bow spring, has its respective ends resting upon the upper bearings 29 of the wringer rolls, being received in enlargements of the upper ends of the slots 51, 150

It has a seat 136 at its middle portion, receiving the lower rounded end of a screw 137, having threaded connection 138 with the inner threaded wall of the sleeve. The screw is provided with a handle 139 for readily turning the same and adjusting the tension of the spring. This spring exerts pressure upon the wringer rolls for properly squeezing the clothes and is resisted by the top bar.

10 The releasing means form easily and quickly acting safety means for releasing pressure between the wringer rolls in case of threatened injury to the operator or to goods.

15 Means are provided for limiting separating movement of the top bar from the main frame so as to prevent flight of the top bar away from the frame, or excessive movement thereof, which might result in injury to the operator or others. These means are exemplified as a supplemental holding means, the coacting holding members 20 of which are normally in spaced relation and are arranged to coact upon release of the latching mechanism.

Thus a latch rod 141 has connection with the 25 top bar. (Figs. 2, 3, 4 and 5). It has a hook 142 forming a slot 143, the hook end of the latching rod being received through a slot 144 in the outer wall of the upright post, being inserted through the space 145 between the bearing 29 for the upper wringer roll and the outer wall of the upright recess in which said bearing is received. When the top bar is released, the hook member 30 is projected upwardly with it, the walls of the slot 143 being received about the upper wall 146 forming the upper end of the slot 144 in the outer 35 wall of the upright post, for limiting the extent of outward movement of the top bar away from the wringer frame. The space 145 is shown as a slot in bearing 29.

40 The holding means are shown of yoke form, there being a pair of the latching rods at the respective sides of the main latching means, connected by a web 149 pivoted in a bearing 150 in the top bar, and exemplified as formed up out of heavy wire having hooks at the respective sides 45 of the latch bar 101, received through upright slots 144 at the respective sides of said latch bar. The holding rods depends from the top bar and the swinging movement of the top bar upon its 50 emergency release tends to throw the holding rods outwardly for insuring engagement between its hooks and the upper end walls of the slot in which they are located. The relation of the holding rod to the bearing 29 is such as to normally direct the holding rod outwardly. The latch rods 141 55 may be swung pendulum wise inwardly out of the slots 144 for removal of the top bar.

In the modification shown in Figs. 10 to 12 inclusive, the outer walls 34 of the upright channels are formed as continuations of the upright flanges and of the bends 48 between the lower ends of said flanges and the outer ends of the shelves.

60 A box-like cross-sectionally substantially U-shaped upright member 151 is formed with an inner wall 152 and side walls 153, the lower ends of which are curved to conform to the curvature of the bend between the base and side flanges of the wringer frame structure. The outer margins of said box-like element are provided with a flange 154, the lower portion of which is curved to correspond with said curvatures. These flanges extend preferably outwardly and are secured, as by welding, to the upright wall, to the base and to the bend between them, for forming

the channel at each end of the frame for receiving the bearings of the wringer rolls.

65 The inner and outer walls of these channels are provided with slots and formations similar to the slots and formations of such walls in the preferred exemplification, and have the clothes guards 61 and the drain board 77 located thereon in similar manner to the clothes guards and drain board in the preferred structure. The outer walls are also provided with securing and latching means and the holding means as in the preferred structure, the lower curved end of the latching bar being secured to the lower bend in the outer wall.

70 The upright flanges preferably terminate at a point below the tops of the upright posts for permitting the top bar to be received over said upright posts. In the preferred form the upper ends of the end plates 45, 46, are provided with inwardly turned flanges 155 fixed to the side walls of the upright channels as by welding. (Figs. 5 and 8). In the modification shown in Figs. 10 to 12 inclusive, the upper ends 156 of the flanges 25 are severed from the body portions 75 of the flanges and are bent inwardly as inturned flanges and fixed to the side walls of the upright box-like parts 151, as by suitably welding the same thereto.

75 The present invention provides a strong wringer frame structure which is compact and so 80 formed as to permit ready passage therethrough of the clothes without injury to or tearing of the clothes, and provides ready manipulation of the parts, as well as quick release of the pressure between the wringer rolls, and prevents excess 85 movement of the movable parts in effecting said release, for avoiding damage and injury.

85 Having thus fully described my invention, what I claim as new, and desire to secure by Letters Patent, is:

90 1. A sheet metal wringer frame structure comprising a base and end upright posts containing upright channels for the bearings of the wringer rolls, said base including draining shelves at the respective sides thereof and said upright posts 95 having side flanges projecting beyond said posts at the respective sides of said posts from the outer end margins of said posts, and bends in the sheet metal in the angles between said shelves and said flanges integral with said shelves and 100 said flanges.

105 2. In combination, a sheet metal wringer frame structure comprising a base and end upright posts containing upright channels for the bearings of the wringer rolls, said base including slanting 110 draining shelves at the respective sides thereof and the outer edges of said upright posts having side flanges at the ends of said shelves projecting laterally beyond said posts at the respective sides 115 of said posts, and bends in the sheet metal in the angles between said shelves and said side flanges integral with said shelves and said side flanges, and a drain board the middle portion of which is pivoted at its ends to the inner portions of 120 said upright posts, said drain board having upturned end flanges which extend into the lateral planes in which said posts are located and spaced from said respective side flanges.

125 3. In a wringer, the combination of a frame comprising an upright post having an upright channel formed by sheet metal walls the inner 130 wall of which has an upright slot for the shafts of the wringer rolls, and a clothes guard comprising a plate having an upright slot for said 135 shafts, the side walls of said last-named slot pro-

- vided with outwardly extending flanges between the side walls of said upright slot in said inner wall for holding said clothes guard against displacement in the plane of said clothes guard, the 5 side and bottom margins of said clothes guard provided with an inwardly extending flange, and said inner wall and said plate of said clothes guard respectively provided with slots having enlarged ends and with headed projections in said 10 last-named slots for holding said clothes guard toward said side wall.
4. In a wringer, the combination of a frame structure comprising a base and upright posts at the respective ends of said base, a top bar 15 connecting the upper ends of said posts, wringer rolls, bearings therefor in said upright posts, pressure means resisted by said top bar exerting pressure between said rolls, a latch normally latching said top bar to said frame structure, releasing means for said latch, and supplemental holding means between said top bar and said frame structure comprising a shank extending between a roll bearing and a wall of a post aforesaid and limiting separating movement of said 20 top bar from said frame structure.
5. In a wringer, the combination of a frame comprising separable sections, wringer rolls operatively located between said sections, pressure means for said wringer rolls, latching means releasably connecting said sections, releasing means therefor, and a shank on one of said sections, said shank having a slot, the other of said sections provided with a keeper normally spaced from said slot and coacting with the walls of said 25 slot upon release of said latching means for limiting separation between said sections.
6. In a wringer, the combination of a frame comprising separable sections, wringer rolls operatively located between said sections, latching means releasably connecting said sections, pressure means for said wringer rolls exerting separating pressure between said sections, a movable releasing part on one of said sections for releasing said latching means, and a pronged limiting 30 yoke about said releasing part, the prongs whereof are provided with latching parts and normally extend into the other of said sections, said other of said sections provided with coacting keeping parts for said latch parts normally spaced from said latch parts and arranged to be engaged by said latch parts upon release of said 35 latching means for limiting separation between said frame sections.
7. In a wringer, the combination of a frame 40 structure comprising a base and upright posts at the respective ends of said base, a top bar connecting the upper ends of said posts, wringer rolls, bearings therefor in the hollows of said upright posts, pressure means resisted by said top bar exerting pressure between said rolls, a latch normally latching said top bar to said frame structure, releasing means on said top bar for 45 said latch, and supplemental holding means between said top bar and said frame structure comprising a yoke having shanks provided with latch parts at the respective sides of said first-named latch and keeper parts therefor, said latch parts and keeper parts normally spaced apart and arranged to coat upon release of said first-named 50 latch for limiting releasing movement of said top bar.
8. A sheet metal wringer frame structure having draining shelves sloping oppositely and downwardly from each other with end uprights formed 55 with upright walls about bearing receiving chan-
- nels and devoid of end walls at one of the ends of said channels, and the respective ends of said respective shelves curved upwardly and forming end flanges extending laterally integral with said end uprights and bent from a single 60 piece of sheet metal into the forms stated. 80
9. In combination, a sheet metal wringer frame structure having oppositely laterally sloping draining shelves with end upright posts having upright end openings throughout the extents of said posts and laterally extending end flanges bent integrally laterally outwardly from said 65 posts and integrally upward with curved bends from the respective ends of said shelves and bent from a single piece of sheet metal, and closing plates fixed across said upright end openings. 85
10. A sheet metal wringer frame structure formed out of sheet metal with laterally extending and downwardly drooping draining shelves and upright cross-sectionally U-shaped posts bent upwardly and integrally from the middle portions of said draining shelves at the respective ends of said draining shelves and laterally extending end flanges integral with the outer end margins of said upright posts and having bends 90 at their lower ends integral with said flanges and the respective ends of said laterally extending 95 downwardly drooping draining shelves. 100
11. In combination, a sheet metal wringer frame structure formed up out of sheet metal with laterally extending and downwardly drooping draining shelves and upright laterally extending end flanges integral with the outer end portions of said shelves and having bends at their lower ends integral with said flanges and the respective ends of said laterally extending 105 downwardly drooping draining shelves, and upright wringer roll bearing receiving posts at the respective ends of the middle portions of said 110 draining shelves and located laterally inward from said laterally extending end flanges. 115
12. In combination, a sheet metal wringer frame structure formed up out of sheet metal with laterally extending and downwardly drooping draining shelves and upright substantially cross-sectionally U-shaped posts bent upwardly 120 and integrally from the middle portions of said draining shelves at the respective ends of said draining shelves and forming upright channels in which bearings for wringer rolls are located 125 and which are open throughout one of their upright ends, and laterally extending end flanges bent from the outer ends of the lateral walls of said upright posts and having bends at their lower ends integral with said flanges and the 130 respective ends of said laterally extending downwardly drooping draining shelves, and separate closing plates fixed to said structure for closing said end upright openings. 135
13. In combination, a wringer frame comprising end upright posts provided with upright channels for receiving wringer roll bearings, laterally extending and downwardly drooping draining shelves between said upright posts and having end portions which curve upwardly at the 140 respective sides of said posts and upright flanges at the outer end edges of said respective posts, and the lower ends of which flanges merge with the upper ends of said upwardly curved end portions, and forming a clothes receiving space 145 which in end extension includes said posts. 145
14. In combination, a wringer frame structure with laterally extending and downwardly drooping draining shelves and upright substantially cross-sectionally U-shaped posts extending up- 150

wardly from the middle portions of said combined draining shelves at the respective ends of said draining shelves and which are open throughout one of their ends, and laterally extending end flanges extending from the outer edges of the lateral walls of said upright posts, and connections between the lower ends of said end flanges and the respective ends of said laterally extending downwardly drooping draining shelves.

15. In combination, a wringer frame comprising end upright posts provided with upright channels and downwardly drooping draining shelves between said upright posts and having

15

end portions which curve upwardly at the respective sides of said posts and upright lateral flanges at the outer end edges of said respective posts, the lower ends of which merge with the upper ends of said upright upwardly curved end portions and forming a clothes receiving space which in end extension includes said posts, and a drain board between said posts having laterally extending ends extending endwise outward beyond the inner margins of said post into the space between the inner margins of said posts and said laterally extending upright flanges.
